GATE OPERATING MEANS

Application filed June 9, 1930. Serial No. 459,972.

This invention relates to openers for gates, doors and the like and more particularly to vehicle operated devices of this character.

5 A primary object of the invention is to so construct an opener of this character that it may be actuated by a lever, which lever after once it is operated may be operated in the same direction any number 10 of times without affecting the opening mechanism and which only becomes operative when the lever is moved in the opposite direction.

Another object of the invention is to so 15 construct a gate opening or other object operating mechanism that a single lever may be employed for actuating it in both directions and which is automatically restored to operative position after it has been actuated by the passage of a vehicle thereover or otherwise and which is so constructed that an ignorant driver or other person cannot injure the device by moving it in the wrong 20 direction.

In carrying out these objects, the invention is susceptible of a wide range of modification without departing from the spirit or sacrificing any of the advantages of the claimed invention; there being shown in 25 the drawings for illustrative purposes a preferred and practical form, in which:

Figure 1 represents a plan view of this improved gate operating apparatus shown applied;

Fig. 2 is a vertical section taken on the line 2—2 of Fig. 1;

Fig. 3 is a side elevation of the operating mechanism;

Fig. 4 is an end elevation thereof;

Fig. 5 is a section taken on line 5—5 of Fig. 3;

Fig. 6 is a view taken on line 6—6 of Fig. 3;

Fig. 7 is a similar view taken on the line 45 7—7 of Fig. 3;

Fig. 8 is a detail perspective of the cam connecting member.

In the embodiment illustrated the device is shown as a gate operating mechanism although obviously it may be used for open-

ing doors, throwing switches and for other purposes. One of these devices is shown located at each side of the gate and being exactly alike one only will be described in detail. Each mechanism comprises a shaft 55 1 rotatably mounted in suitable bearings 2 mounted on bases 3 of any desired construction. This shaft 1 has a crank portion 5 designed to be located in the path of vehicles which pass through the opening 60 closed by the gate 50. This crank portion 5 is normally in upright position as shown in Figs. 1 and 3 and when contacted by the wheels of the vehicle is forced down into horizontal position and thereby opens or 65 closes the gate 50 in accordance with the direction in which the vehicle is going as will be hereinafter more fully described.

One end of the shaft 1 has fixed thereto by keying or otherwise a disk-like plate 70 or wheel 6 which is provided on one face thereof with laterally extending lugs 7 which are designed to cooperate with similar lugs 9 on a disk or wheel 8 loosely mounted on shaft 1 as shown clearly in 75 Figs. 2 and 3. These lugs 7 and 9 which are designed for interlocking engagement when the shaft is turned in one direction or the other are so located in relation to each other that after the gate has been shut by 80 the passage over the crank portion 5 thereof of the vehicle the member 8 will remain in the position where it was placed by the turning of the shaft and the engagement of the lugs 7 with the lugs 9 thereof and the 85 wheel 6 under the action of the mechanism now to be described will move freely so that lugs 7 will pass away from lugs 9 without affecting the position of wheel 8 so that the shaft 1 may rock back and forth without changing the position of the gate 50 90 with which the member 8 is connected. This is due to the space which is provided between the lugs on the two members 6 and 8 and which is in the nature of a dental coupling thereby providing sufficient lost motion between the wheel trip member 6 and the gate throw member 8 to provide for the passage of following vehicles without affecting 95 the position of the gate.

As shown a rod 20 connects the two gate operating mechanisms with each other and with the gate 50 although obviously other suitable means may be employed. The means connected with the gate 50 and with the rod 20 for swinging the gate to open or closed position when the vehicle operated means is actuated is indicated at 60 and may be of any desired construction. It constitutes no part of the invention and hence it is not deemed necessary to show a detailed construction thereof.

Mounted on one of the base plates 3 over the outer end of shaft 1 are two upstanding inverted V-shaped braces or standards 10 and 11 in which is journaled a shaft 12. Carried by said shaft are two sleeve members or sockets 13 and 14 designed to receive connecting rods 15 and 16 connected respectively with the fixed wheel or disk 6 and the loose disk 8. Coiled springs 17 and 18 are carried respectively by rods 15 and 16. The connecting rod 15 has a collar 15a thereon against which one end of the coiled spring 17 abuts while the other end thereof extends into the socket member 13 and abuts against the bottom of the socket therein.

The rod 16 has a yoke-shaped head 19 the arms of which are pivotally connected with a link or lever 21 carried by the member 8 and which as shown is fixedly connected with said member being either made integral therewith or rigidly secured thereto in any suitable manner. The coiled spring 18 abuts at one end against the yoke head 19 and at its other end against the bottom of the socket in the member 14 and exerts its tension to hold the member 8 in the position into which it is thrown by turning of the shaft 1 incident to the passage of a vehicle over the said crank portion 5 of said shaft and which is effected by engagement of the cooperating lugs 7 and 9 on the fixed and movable members 6 and 8.

The coiled spring 17 exerts its tension to return the shaft 1 to initial position after the passage of the vehicle so that an oncoming vehicle when engaging the crank portion 5 and turning the shaft 1 will not affect the position of the member 8 and thereby allow the gate 50 to remain in open position.

The connecting rod 15 has a head 22 with an opening 23 therein which is designed to fit over a correspondingly shaped lug 24 made integral with a boss 25 carried by the member 6. This boss 25 which is shown made integral with the disk 6 is eccentrically arranged relatively to the shaft 1 as shown clearly in Figs. 4 and 5 and the bolt 26 which connects the head 22 with the lug 24 has a washer 27 arranged thereon whereby the head is clampingly and securely held engaged with the boss. This eccentric connection of the head with the wheel adapts the spring 17 to return and hold the shaft 1

normally with the crank portion 5 in vertical position. An arm 21 extends radially from wheel 8 and is connected with rods 20 and 16 by a bolt 21a.

The spring pressed rod 16 of the disk 70 wheel 8 operates to hold the member 8 in the position to which it is forced on the turning of the shaft 1 by the passage of a vehicle over the crank portion 5 which movement operates to open the gate. 75

In the operation of this device the parts being in the position shown in Fig. 1 with the gate closed the crank portion 5 of the shaft 1 will be in vertical position and the lever or arm 21 over the center on one side 80 of the upright and held in this position by the coiled spring 18 and in which position the gate is held closed.

When a vehicle approaches and contacts the crank 5 it forces said crank down and into horizontal position turning the drive shaft 1 and causing lugs 7 on the fixed disk 6 to engage those 9 on the movable disk 8 thereby turning said disk 8 and throwing the lever 21 on the opposite side of the center of gravity. This moves rod 20 longitudinally and pulls the gate lever to position for opening the gate, and it is held in open position by means of the spring 18. The disk 6 is returned to initial position 95 by the coil spring 17 without its lugs engaging those on the member 8 due to the proper spacing of the lugs on the two members. It will thus be seen that the drive shaft 1 may be operated in the same direction any number of times without any further effect on the gate opening mechanism until the latter is operated in the opposite direction. This provides for the passage 100 of following vehicles over the eccentric or 105 crank 5 in the same direction after the gate mechanism has been actuated to open the gate without in any way affecting such mechanism.

When the eccentric or crank shaft 5 is 110 moved in the opposite direction by a vehicle coming that way the lugs 7 on disk 6 will engage those 9 on disk 8 and throw the lever 21 past the center of the opposite side of the center of gravity and thus exert 115 a pulling action on the gate lever which will cause the gate to be closed. The gate will be held in this position by the coil spring 18 until the drive shaft is again operated in the opposite direction. 120

It is of course understood that the two gate operating mechanisms, located one on each side of the gate, are designed one to open the gate as the vehicle approaches in one direction and the other to close it as 125 the vehicle passes through and leaves the gate. The two are shown connected by the rod 20 which is also connected with the gate by any suitable actuating means as is indicated in Fig. 1. Thus when the vehicle 130

passes through in the reverse or opposite direction the mechanism that formerly shut the gate will open it, and the one that formerly opened it will close it.

- 5 The gist of the invention resides in the lost motion provided between the members 6 and 8 which permits the crank member 5 to be operated in the same direction any number of times after it has been once 10 turned to open the gate and this permits the use of a single wheel trip thereby avoiding the trouble which has been encountered with gates having two trip levers.

It is of course understood that the form 15 illustrated shows one means of providing a loose coupling between the wheel operated lever and the gate controlling mechanism to allow the former to return to upright position without operating the gate throwing 20 mechanism.

While the return of the crank member 5 to vertical position is here shown accomplished by the use of springs it is of course understood that other equivalents may be 25 used for this purpose.

The use of this mechanism prevents ignorant drivers from running over the wrong eccentric because there is only one and if the driver should pass in the wrong 30 direction it will only be pushed to horizontal position with no effect on the gate opening mechanism, and upon the passage of the vehicle it will immediately assume vertical position ready for the next actuation. This 35 avoids all danger of the opener being injured.

Without further description it is thought that the features and advantages of the invention will be readily apparent to those 40 skilled in the art, and it will, of course, be understood that changes in the form, proportion and minor details of construction may be resorted to, without departing from the spirit of the invention or its scope as 45 claimed.

I claim:

1. A gate operating mechanism comprising a crank shaft with the crank portion thereof located in the path of passing vehicles, a member fixed to said shaft, a co-operating member loose on said shaft, gate opening means connected with said loose member and interengaging elements carried by said members and so spaced as to provide lost motion between the members to permit one member to be moved relatively to the other after its first actuation without affecting said member, and means for holding said members in operative position.
2. A gate operating mechanism comprising a crank shaft with the crank portion thereof located in the path of passing vehicles, a member fixed to said shaft, a co-operating member loose on said shaft, gate opening means connected with said loose

member, interengaging elements carried by said members and so spaced as to provide lost motion between the members to permit one member to be moved relatively to the other after its first actuation without affecting said member, and means for holding said members in operative position, said loose member being connected with the gate opening means.

3. In a gate operating mechanism, a crank shaft, with the crank portion located in the path of passing vehicles, two members mounted on said shaft, one being fixed thereto and the other movable thereon, cooperating lugs on the opposed faces of said members and spaced in relation to each other so that when after the fixed member operates the movable member it may be turned in the same direction any number of times without affecting the movable member, and a gate opener connected with said movable member.

4. In a gate operating mechanism, a crank shaft with the crank portion located in the path of passing vehicles, two members mounted on said shaft, one being fixed thereto and the other movable thereon, cooperating lugs on the opposed faces of said members and spaced in relation to each other so that when after the fixed member operates the movable member it may be turned in the same direction any number of times without affecting the movable member, a gate opener connected with said movable member, and resilient means for holding said members in operative position.
